UNITED STATES PATENT OFFICE.

EDWARD N. LA VEINE, OF KANSAS CITY, MISSOURI.

DESIGN FOR A CUFF-HOLDER.

SPECIFICATION forming part of Design No. 30,389, dated March 28, 1899.

Application filed February 27, 1899. Serial No. 707,112. Term of patent 7 years.

To all whom it may concern:

Be it known that I, EDWARD N. LA VEINE, of Kansas City, Jackson county, State of Missouri, have invented a new and original Design for a Cuff-Holder, of which the following is a full, clear, and exact description, reference being had to the accompanying drawings, forming a part thereof.

Figure 1 is a plan view of a cuff-holder embodying my new design. Fig. 2 is a side elevation thereof, and Fig. 3 is a rear elevation.

As shown in the drawings, the leading or material feature of my design consists of a straight shank or body 1, having the transverse depression 2 at a point near its center, and the rear end of said shank or body is bifurcated or formed into the outwardly and downwardly projecting ears 3, and upon each of said ears is arranged a short shank 4, terminating in a spherical body 5. The forward end of the shank or body 1 is curved laterally, as indicated by 6, and extending upwardly

from the shank or body between this curved forward end and the depression 2 is a pair of ears 7, the same supporting the straight plate 8, the forward end of which is curved in conformity with the curved forward end of the shank or body 1. The forward end of this plate 8 is provided with a downward extension 9, which rests upon the forward end of the shank or body 1.

The tops of the body 1 and plate 8 are ornamented with slightly embossed or raised figures 10.

I claim—

The design for a cuff-holder, substantially as herein shown and described.

In testimony whereof I affix my signature in presence of two witnesses.

EDWARD N. LA VEINE.

Witnesses:

ROSS T. THOMAS;
MARION BIGLEY.
